UNITED STATES PATENT OFFICE.

NICOLAY GREVSTAD, OF CHICAGO, ILLINOIS.

DESIGN FOR A CAMPAIGN SOUVENIR.

SPECIFICATION forming part of Design No. 23,644, dated September 18, 1894.

Application filed August 6, 1894. Serial No. 519,624. Term of patent 3½ years.

To all whom it may concern:

Be it known that I, NICOLAY GREVSTAD, a citizen of the United States, residing at Chicago, in the county of Cook and State of Illinois, have invented and produced a new and original Design for Campaign Souvenirs, of which the following is a specification, reference being had to the accompanying drawings, showing the design.

10 Figure I of the drawings is a perspective of the device and Fig. II is an elevation of one of its ends.

The leading features of my design consist in a semicylindrical body portion, its curved 15 portion being slightly bowed or enlarged between its ends and having a series of raised bands across it near each end and a bust of a woman projecting from one end of the body

portion. One end of the body portion has two small apertures, and is flat. Projecting from the opposite end of the body portion is the bust of a woman, the head being thrown back so that the face is turned outwardly or away from the body portion; the features and hair being typical of the Kanaka race and the 25 head being surmounted by a crown, emblematical of royalty.

I claim—

The design for a campaign souvenir, substantially as described and shown.

In testimony whereof I hereunto set my signature in the presence of two witnesses.

NICOLAY GREVSTAD.
